G. E. KELLAR.

PIPE MOLD.

APPLICATION FILED DEC. 16, 1915.

1,278,479.

Patented Sept. 10, 1918.

UNITED STATES PATENT OFFICE.

GEORGE ELMER KELLAR, OF LOS ANGELES, CALIFORNIA, ASSIGNOR TO KELLAR-THOMASON COMPANY, A CORPORATION OF CALIFORNIA.

PIPE-MOLD.

1,278,479.

Specification of Letters Patent. Patented Sept. 10, 1918.

Application filed December 16, 1915. Serial No. 67,161..

To all whom it may concern:

Be it known that I, GEORGE E. KELLAR, a citizen of the United States, residing at Los Angeles, in the county of Los Angeles and State of California, have invented certain new and useful Improvements in Pipe-Molds, of which the following is a specification.

This invention relates to improvements in mold devices and has particular reference to pipe molds, such as are commonly used for the formation of cement concrete or other pipes adapted for various uses and more especially for irrigation purposes.

15 It is an object of the invention to provide a mold with a split jacket and having means whereby it may be opened starting with any given point along the length of the mold and extending progressively therefrom to the end or ends of the mold, whereby the mold is pulled away from the concrete article without the usual suctional effect whereby the pipe is frequently split or broken.

25 It is also an object of the invention to provide a mold having a split jacket adapted to be spread sufficiently to take the mold from the article formed, said mold having fastening means for drawing the same together or separating it, one or more of said 30 fastening means being of a yielding character whereby a portion of the mold will open before the remainder thereof has become spread apart thus avoiding the splitting or 35 cracking of the article formed.

With these and other objects in view the invention comprises certain novel constructions, combinations and arrangements of parts as will be hereinafter more fully described and claimed.

In the accompanying drawing:

Figure 1 is a side elevation of a mold made in accordance with this invention, the parts being closed.

45 Fig. 2 is a similar elevational view but with a portion of the jacket open showing how the mold opens gradually toward one end from the other.

Fig. 3 is a transverse sectional view taken upon the line 3—3 of Fig. 1, the mold being 50 in its closed position.

Fig. 4 is a fragmentary detail sectional view showing the meeting edges of the mold as partially separated.

Fig. 5 is a fragmentary detail sectional 55 view through one side of the mold taken upon the line 5—5 of Fig. 1.

Fig. 6 is a side elevation upon a reduced scale of a mold having more than two fastening devices thereon.

The mold constituting the subject matter of the present invention is adapted to mold any articles where an outer casing or jacket is employed which is capable of being expanded or partially opened for removing it 65 from the article or device molded.

It is especially adapted for use in the making of concrete pipes, such for instance as are commonly employed for irrigation, drainage or sewerage purposes. In making 70 piping with a mold of this kind, an inner mold member is adapted to be used and an outer mold member or jacket, both members being split whereby the inner one may be contracted for removing it, and the outer 75 one may be expanded also for removing it. Molds of this character heretofore have been so constructed that they open equally and simultaneously from top to bottom or from one end to the other. This is an effective 80 construction when the concrete or other plastic material is not used in a very wet condition. In order to make better piping however, it is desirable to have the cement concrete quite wet, so that when molded it 85 is approximately of a jelly like consistency so that if jarred it would shake somewhat like jelly and for this reason has been given a name in the art, being known as liver concrete. In making piping of concrete in this 90 condition it has required a great deal of care in opening the mold to prevent the splitting or cracking of the pipe. With the present invention a new principle of operation has been devised and by opening the mold with 95 a start made at a given point along the

length thereof and gradually continuing to open it until the opening extends from end to end of the mold, it is found that the mold may be quickly removed and yet without danger of cracking or injuring the moist pipe. The preferred manner of carrying out this invention has been shown in the drawing and the details and features of the invention will now be more specifically described with reference thereto. In said drawing 6 indicates a casing or jacket preferably formed of a sheet of metal of suitable thickness, rolled and shaped in the desired form, so that its edges may be brought together at 7 to form a complete inclosure. The jacket is also provided with a lapping piece 8 secured to one edge of the jacket as at 9 and adapted to slip over and open the other edge to a suitable distance to form a complete closure. The jacket may be strengthened if desired by strengthening strips or bands 10 and 11 applied at the upper and lower edges of the said jacket respectively. The ends of the said strengthening bands or strips abut against each other when the jacket is closed. Means is employed, which is preferably operated by one hand for contracting the jacket and bringing it into its molding position, the said means being also capable of spreading the abutting edges of the jacket whereby the jacket can be readily removed or lifted from the pipe or other molded article. The mechanism illustrated comprises a shaft 12 extending longitudinally of the mold and having rigidly secured thereto arms 13 and 14 preferably fastened to the end portions of said shaft. The inner ends of said arms are pivoted at 15 to brackets 16 which are rigidly fastened to the jacket, and usually upon the lapping piece 8 thereof. A handle 17 is also rigidly fastened upon the shaft 12. The outer end of the handle is bent so that when the mold is closed the handle will still be spaced from the sides of the mold, and an adjustable screw bolt 18 carried by the end of said handle controls the amount of such spacing as will be clearly understood by reference to Fig. 3 of the drawing. The shaft 12 by reason of its mounting upon the arms 13 and the pivots 15 will swing about the said pivots 15 when the handle 17 is grasped and moved from one side to the other, the opposite site positions being shown in Figs. 3 and 5 of the drawing. The handle 17 also affords one hand hold for lifting the mold and operating the mechanism for opening and closing the same. For convenience also in lifting the mold a stationary handle 19 is fastened to the wall of the jacket 16 upon the side thereof opposite to the handle 17, when the latter is in its closed position. In order to connect the shaft with the other

edge of the jacket from that upon which the said shaft is mounted, linking means is interposed between the parts, the links at one end thereof comprising a goose neck member 20 having an enlarged eye or bearing portion 21 adapted to loosely engage the shaft 12, whereby said shaft may be turned within the same. The opposite end of said member 20 is provided with a screw threaded socket adapted to receive a threaded bolt 22. The outer end of the bolt 22 is provided with an eye 23 which is secured by a pivot pin 24 to a bracket 25, which is bolted to the adjacent wall of the jacket outside the edge of the lapping piece 8. The bracket 25 also has a curved projecting portion 26 adapted to extend over the lapping piece 8 for guiding it in its movement as the mold is closed or opened.

The mold is also provided at other points along its length with linking means and near the opposite end of the mold from the device just described, with a linking means made up of a goose neck piece 27 having a screw threaded socket adapted to receive a threaded bolt 28. The bolt 28 passes through an aperture 29 formed in a lug 30 which projects from a bracket 31. The outer end of the said bolt 28 is provided with a nut 32 and a spring, preferably of the helical type as 33 interposed between said nut 32 and the lug 30. The bolt is free to pass back and forth through the aperture 29 to a limited degree at intermediate portions of the motion imparted to the link mechanism. The spring 33 bearing against the nut 32 tends to move the bolt 28 outwardly through the passage 29 until the end of the goose neck piece 27 strikes the lug 30, when the lever or handle 17 is thrown open before the arm 13 and the goose neck 27 begin to force the jacket walls apart, after which the lug will be moved by the continued action of the goose neck 27 for spreading the jacket edges at the top. In order to cause the said bolt 28 to bring the edges of the jacket tightly together at the end of the jacket closing movement, in contracting the mold, a key or other detent 34 is so placed upon the said bolt 28 that when the handle 17 has been finally pushed to its closed condition in contracting the mold, the bracket 31 will have been moved as far as it can go in that direction and until the edges of the jacket walls have been made to come together as at 7. The link connection just described will thus be observed as of a yielding character as compared with the other link connection hereinbefore described. In opening the mold, when the shaft 12 is thrown about its pivotal supports by the operation of the handle 17, the link construction at the bottom of the device as illustrated in Figs. 1 and 2 will immediately begin to push the

lower portions of the jacket open, by reason of the positive connection between the goose neck member 20 and the bracket 23. At the upper end of the mold however, the bolt 28 having a longitudinal slip movement through the aperture 29 will first slide through said aperture under the action of the spring 33 whereby the upper part of the mold will at first remain closed, and in this position 5 until the end of the upper goose neck member 27 engages the lug 30 of the bracket 31, and positively pushes the parts of the mold apart at the upper end thereof. The lug 30 is so positioned that when engaged by the 10 said member 27 it will finally be moved to open the upper end of the mold to a sufficient extent to free the pipe, while the lower end has been opened also to the extent of its link mechanism. The suction between the 15 walls of the jacket and the moist cement is relieved by thus pulling the mold away gradually so that there is no danger of pulling the cement pipe apart or cracking it where the mold opens. In closing the mold 20 the handle 17 is thrown from the position shown in Fig. 4 to the position shown in Figs. 1 and 3. This will cause the link mechanism to pull the mold together again. The key 34 is so set that the bolt 27 will be 25 pulled back through the opening 29 only a short distance, the key insuring of the parts being drawn the same distance at one end of the mold as at the other.

It will be evident that the yielding link 30 mechanism may be arranged at either end of the mold, for it makes no difference which end is pulled apart first, it only being necessary to pull a portion of the mold apart first and then allow the remaining portions there- 40 of to follow progressively.

As shown in Fig. 6 of the drawing, it will be seen that more than one molding connecting may be employed and that more than two mold operating connections may 45 be used according to the length of the mold. Where a larger number of connections are used as shown in said Fig. 6, the intermediate connection as at 35 is also of a yielding character being provided with a spring 36 50 and otherwise formed as hereinbefore described with respect to the upper link construction of Figs. 1 and 2. With this form of the device the upper portion of the mold will be open first by the movement of the 55 positive connection. At the same time the other two will yield without opening the lower portion of the mold until the opening operation is nearly completed when the lower portions of the mold will be brought 60 up to the same movement as the other portion. The extent of divergence between the open edges of the jacket need not be very great, as will be understood by looking at the V-shaped opening in the mold shown in

Fig. 2. Such slight divergence is however, 65 productive of the desired result and makes it possible to take pipes or other articles made of "liver" concrete out of the mold without danger of cracking or parting it at any point. The inner lining or mold employed 70 in making piping as indicated at 37 in Fig. 3 may be of any desired form being usually 75 of the piece of sheet iron or steel turned into the same shape as the outer jacket but of less diameter so as to form a space between the parts to receive the material to be molded. Any desired mechanism as indicated at 38 may be used if preferred for contracting the said inner mold when it is to be removed from the pipe after it has been 80 molded.

It will be evident that many of the parts may be varied and mechanical equivalents substituted therefor, without departing from the spirit and scope of the invention. 85

It will be observed also that when the jacket is made in sections hinged together, as when of cast material, the operation of the opening and closing mechanism will be practically the same as when said jacket is made 90 in one piece of sheet metal capable of springing apart, as above described.

What is claimed is:

1. A pipe mold for cement concrete pipes comprising a divided jacket having its edges 95 adapted to be brought together to permit the shaping of a pipe, a mechanism for opening and closing the jacket comprising a shaft adapted to be moved about an external center, the said shaft being mounted upon one 100 edge of said jacket, a bracket upon the other edge of the jacket, and connecting links interposed between one of said bracket and the shaft for positively moving the edges of the jacket toward and away from each other, 105 a bracket having an opening therein at another point upon said jacket, a link connected with the shaft and having a projection adapted to extend through said bracket, a spring tending to draw said projection 110 through said opening and a key limiting the movement of said projection, whereby one portion of the mold may be opened ahead of another portion thereof for pulling the mold off of the article in a diagonal direction. 115

2. A pipe mold comprising a divided jacket and having means for drawing the edges together made up of a shaft, means for swinging the shaft with an eccentric 120 movement, links opposite different portions of the mold connecting said shaft with an edge of the mold, one of which is adapted to move the edges positively with respect to each other while another is provided with 125 a yielding link, mechanism whereby an edge is not moved positively at that point at the beginning of a movement of said shaft, but

is moved positively toward the end of a movement in either direction.

3. A pipe mold, comprising a split jacket, clamps supported at different positions 5 across the split in the jacket, one at least of said clamps being a positive, and one at least of said elements being a yielding clamp, and a rigid connection between said positive clamp and said yielding clamp, whereby one

portion of the mold may remain closed until other portions have been opened.

In testimony whereof, I have hereunto set my hand, in presence of two witnesses.

GEORGE ELMER KELLAR.
